UNITED STATES PATENT OFFICE.

GEORGE H. RUPLEY, OF SCHENECTADY, NEW YORK.

ELECTRIC CLOCK-WINDING MECHANISM.

No. 832,747.

Specification of Letters Patent.

Patented Oct. 9, 1906.

Application filed July 14, 1905. Serial No. 269,623.

To all whom it may concern:

Be it known that I, GEORGE H. RUPLEY, a citizen of the United States, residing at Schenectady, in the county of Schenectady and State of New York, have invented certain new and useful Improvements in Electric Clock-Winding Mechanisms, of which the following is a specification.

This invention relates to means for automatically winding clock mechanisms, and has for its object the provision of a means of this character whereby an electric current will be periodically utilized to effect the winding of the clock mechanism after a predetermined amount of the spring has uncoiled.

One of the objects of my invention is to provide an electric clock-winding mechanism which may be connected with an ordinary lighting or power circuit and which will wind and rewind at stated intervals and will require no attention whatever.

A further object is to provide means whereby the clock mechanism will continue to operate for a definite period in case the electric power should not be available when the time comes for the mechanism to be wound, arrangements being made whereby when the power does come on the winding mechanism will immediately start and take up the slack in the spring.

A still further and very important object of this invention is to provide against the complete running down of the clock mechanism, since whenever this occurs the clock mechanism gets out of adjustment and the services of an expert are required to adjust it.

Broadly stated, therefore, my invention comprises the combination, with a clock mechanism, of an electromagnetic device which at stated intervals will wind the clock, but which should the power fail to come on will run for another interval and will then absolutely stop with the circuit closed, so that when the power does come on it will immediately wind up the spring which has uncoiled during the second interval.

My invention further consists in the details of construction and in the arrangement and combination of elements hereinafter set forth, and particularly pointed out in the claims annexed to and forming a part of this application.

In the drawings, Figure 1 is an elevation of 55 a clock-winding mechanism embodying my

improvements. Fig. 2 is a plan view of the same. Fig. 3 is an end elevation of the mechanism. Figs. 4 and 5 are details of certain parts of the time mechanism. Fig. 6 is a section on line 6 6 of Fig. 1. Fig. 7 is a diagram 60 of the circuits. Fig. 8 is a perspective detail of the retaining-hook and its operating parts. Fig. 9 is a perspective detail of the reserve-wind mechanism, and Fig. 10 is a view similar to Fig. 1 with the parts shown 65 in a position assumed while the mechanism is winding.

Referring to the drawings, 10 is an electric motor connected by a train of gearing with the shaft 11, the motor being preferably 70 geared down to the shaft, so as to drive it at a slower speed. I prefer to use an electric motor to effect the winding, though any other electromagnetic device might be employed. Loosely mounted upon the shaft 11 is the 75 spring-drum 12, provided with a mainspring having its inner end fixed to the shaft and its outer end to the drum in a manner common in mechanisms of this character. The gear 13, mounted to rotate with the drum, drives 80 the time mechanism, in the usual manner through gearing 14. The spring-drum is provided with a long hub 15, which has a bearing in the clock-frame 16. Loosely mounted upon this hub is a slip-collar 17, 85 having a projecting portion 18, provided with a pin 19, extending in a direction longitudinally of the hub, so as to engage with the slotted disk 20. This disk is fixedly mounted on the hub 15 and is provided with a V-shaped slot having radial sides 21 and 22, which limit the movement of the collar 17 with respect to the disk. Loosely mounted upon the hub and upon the opposite side of the disk from the collar 17 is another collar 90 23, provided with an elongated arm 22', having at its outer end a pin 23' for making contact, as hereinafter set forth. This collar 23 is spring-pressed in a clockwise direction by means of spring 24', one end of which is fixed to the hub and the other end to the collar at 95 25'. Adjacent to the spring 24' is a collar 24, rigidly secured to the hub 15. The shaft 11 extends beyond the end of the hub, and on this portion of said shaft is rigidly secured a hub 25, provided with two cams 26 and 27, which therefore rotate when the motor rotates the shaft 11 and winds the spring. It will be obvious from this construction that the parts mounted on the hub 15 will turn at 100 110

the same speed as the spring-barrel 12. They might be turned at a slower speed if the turning interval for winding be desired longer by mounting said parts on an auxiliary shaft, 5 driven by reducing-gearings.

- Mounted in the bearings 28 and 29 of the bracket 30 is a tube 31, provided with a set-collar 32, having a finger 33 extending upward and at right angles toward the frame.
- 10 A coiled spring 34 presses against the collar 32 and bearing 28, so as to force the tube 31 toward the cam 26. A plunger 35 reciprocates back and forth in the tube and is also pressed, by means of a spring 36, in the direction of the cam. The plunger 35 has attached thereto a pin 37, which projects through the slot 38 in the tube. Pivoted at 39 to an extension of the bracket 30 is an arm 40. The rear portion of this arm is provided with a lug 41, which is engaged by the pin 37. This lug is provided with a cam-shaped notch 42, into which the pin 37 fits. The opposite end of the arm is formed into a hook 43, which is adapted to engage the pin 23' to latch it in place. As the plunger 35 is moved backward by engaging the cam 26, the pin 37 engages the lug 41, depressing the hook 43 over the pin 23'. Spring 44 presses against the lug 41 to normally hold the hook 30 in a raised position. Mounted to reciprocate in a bracket 45, secured to the frame, is a rod 46, also provided with a set-collar 47 and spring-pressed by means of a spring 48 in a manner similar to the sleeve 31. Pivoted at 35 49 to this rod is an arm 50, which is pressed downward by means of the spring 51, secured to the collar 47. The outer extremity of the arm 50 is of insulating material 52 and is provided with a notch 53, in the bottom of 40 which is a contact 54 in electrical connection with arm 50. The pin 23' is adapted to enter this notch and close the motor-circuit at 54. Projecting laterally from the arm 50 is a stud 55, to which is secured an adjustable 45 depending arm 56, which is engaged at its lower end 57 by the cam 27. The rotation of the cam thus raises the arm 50 about pivot 49 against the tension of the spring 51. The insulated portion 52 of the arm 50 is cut 50 away at 58, so as to provide an abutting shoulder for the pin 23' when it is not in the notch 53 and to prevent the arm 50 from moving forward. The arm, however, follows the 55 time mechanism until stopped by collar 47. The finger 33 of the collar 32 engages a projection, such as screw 59, on the rod 46, moving it backward against the tension of the spring 48.
- 60 The operation of the mechanism is as follows: With the parts in the position shown in Fig. 1 the pin 23' is resting on the insulating material, and the motor-circuit is therefore open, a winding having just taken place. As 65 the clock mechanism runs the drum 12 ro-

tates in the direction of the arrow, Fig. 2, carrying with it the disk 20. The collar 23, having thereon the contact-pin 23', follows the disk around, since it is being spring-pressed in that direction. The arm 22' by 70 engaging the pin 19 presses it against the radial side 22 of the V-shaped slot of the disk 20, carrying the pin around, as shown in full lines in Fig. 9. When the drum has made a revolution, which will be at the end of a certain 75 period—say, for instance, an hour—the pin 23' comes opposite the notch 53, and when it enters the notch the motor-circuit is closed at the contact 54. The motor now starts, rotating the shaft 11 and carrying with it the 80 cams 26 and 27. As soon as the motor starts to rotate the plunger 35 is engaged by the cam 26 and forced backward, causing the pin 37 to engage lug 41 and raise the same to depress the hook 43 over the pin 23', as 85 shown in the dotted lines in Fig. 8. The arm 56 is then engaged by the cam 27, raising the arm 50, as shown in Fig. 10, thereby disengaging the contact-pin 23' from the notch 53, breaking the motor-circuit. An 90 auxiliary circuit, however, has meanwhile been closed through the cam 26 and plunger 35 through the metallic frame and conductor 60 back to the motor. The two operations of depressing the hook 43 and raising the arm 50 may be simultaneously performed, it being essential, however, that the arm 50 should not be raised sufficiently to release the pin 23' from the notch 53 until the hook 43 is depressed over the pin. It is 95 also important that the circuit should not be broken at 54 until the auxiliary circuit is closed between the cam and the plunger, and this is accomplished by so arranging the cams 26 and 27 that the former engages 100 the plunger 35 before the latter lifts the arm 50 away from pin 23' to break the contact at 54. After the arm 50 has been raised by means of cam 27 and arm 56 sufficiently to clear the pin 23' the finger 33 engages screw 59 and carries the rod 50 backward against the tension of the spring 48, as shown in the dotted lines in Fig. 10, so that when the cam 27 allows the rod 50 to descend the pin 23' will engage with the abutting portion of the insulating material. 110 The motor will continue to rotate, driving the cam 26 in the direction of the arrow, Fig. 1, until a complete revolution is accomplished. The cam 26 is cut away sharply at this point, so that the plunger 35 and the sleeve 31 are returned by their respective springs, the motor-circuit being broken, since the plunger no longer engages with the cam. As the sleeve 31 moves forward in response to the pressure of its spring finger 33 is carried forward from 115 screw 59, releasing the rod 46, which also moves forward in response to its spring 48, carrying the abutting portion forward until it engages with pin 23', as shown in Fig. 1, and also carrying the notch 53 forward to a 120

position where it will again engage the pin 23' when the latter makes a revolution. The notch will be in this position when the collar 47 reaches the end of the bracket 45. This 5 operation will be repeated at predetermined intervals, depending upon the gearing of the clock, the period which I have chosen for illustration being one hour. It oftentimes happens, however, in lighting-circuits that the 10 current is off for a period of time, and this failure of current is liable to occur at the time when the contact is made for the motor to wind. In case this should happen my clock mechanism will continue to run for another period 15 equal to the interval between windings. The pin 23' will remain in the notch 53, thereby closing the motor-circuit, so that the motor will be in readiness to start when the current does come on. The time-train operates, carrying with it the disk 20 and the pin 19 against the increasing tension of the spring 24'. If at any time during this period the current should come on, the motor will start and rotate the cams 26 and 27. The hook 43 20 will be depressed by means of cam 26, plunger 35, pin 37, and lug 41, and the arm 50 will be raised through cam 27 and arm 56. When the shaft 11 and the cams 26 and 27 attached thereto have made a complete revolution, 25 the hook 43 will be raised and the arm 22' will be free to respond to its spring tension and rotate until it reaches the stop-pin 19, which has reached an intermediate point, depending upon the length of time the mechanism 30 has run before the motor starts. The clock then continuing to run, another winding will take place as soon as the pin 23' reaches the notch 53. If, however, the current fails to come on during the entire period, 35 the clock mechanism will continue to run; but when the pin 19 reaches arm 22', which is locked in notch 53, the mechanism will be positively stopped. The object of the latching-hook 43 is to prevent the clock from running down in case the current should go off 40 during the winding-up operation, at which time the arm 50 being raised the arm 22' would not be stopped at the end of its period, and therefore the pin 19 would continue to rotate until the spring had entirely uncoiled. 45 This feature would be very objectionable, since it would necessitate a manual winding and the adjustment of the mechanism by an expert. The motor connections are as follows: 50 One terminal is grounded in the mechanism by means of conductor 60, connected with any convenient portion of the mechanism—as, for instance, bracket 30, insulated from the clock-frame 16 by insulating-block 30'. The 55 other terminal is conveniently connected with shaft 11, likewise insulated from the clock-frame by means of insulating-sleeve 16'. The circuit will thus be closed from shaft 11 through the mechanism either by means of 60 pin 23' and contact 54 or cam 26 and plunger

35, the arm 56, which would be the only other path of the current, being insulated from the shaft by means of insulated cam 27.

It will thus be seen that I have provided a mechanism which will be automatically wound at predetermined intervals by simply making connections with the ordinary lighting or power circuit, that the mechanism can never absolutely run down, that provision is made against the failure of current for a definite time, and that the motor-circuit is always closed at the time when the motor is supposed to be wound, regardless of whether the current is on or off.

What I claim as new, and desire to secure 80 by Letters Patent of the United States, is—

1. The combination with clock mechanism, of means for automatically winding the same comprising an electric motor, means for closing the circuit of said motor to wind said mechanism after a predetermined amount of spring is uncoiled, means whereby said spring further uncoils a predetermined amount to drive said clock mechanism upon the failure of said motor to operate, and means whereby 85 the energy expended by the said further uncoil is immediately restored when the motor operates.

2. The combination with clock mechanism, of means for automatically winding the 95 same comprising an electric motor, means for periodically closing the motor-circuit to wind said mechanism, means for operating said mechanism for a predetermined period after the expiration of said first period upon the 100 failure of said winding means to operate, and means whereby said motor is caused to restore the energy expended during said latter period immediately upon the starting up of 105 the motor.

3. The combination with a clock mechanism, and a mainspring therefor, of means for automatically winding the same comprising an electric motor, means for closing the motor-circuit after a predetermined amount of 110 uncoil of said mainspring to rewind the same, means whereby said spring is uncoiled a further predetermined amount to actuate said clock mechanism upon the failure of said motor to operate, and means whereby the taking up of all of the slack in said spring due to 115 said second uncoiling is effected immediately upon the starting up of the motor.

4. The combination with clock mechanism, of winding mechanism therefor including an electric motor, contact-terminals for closing said motor-circuit at predetermined intervals, one of which terminals is carried by said clock mechanism, means whereby the motor-circuit is opened at said terminals 120 upon the starting of the motor and simultaneously closed independently of the clock mechanism, and means whereby the latter circuit is broken after a predetermined movement of said winding mechanism.

5. The combination with clock mechanism of winding mechanism therefor including an electric motor, contact-terminals for closing said motor-circuit at predetermined intervals, one of which terminals is carried by said clock mechanism but yieldingly connected therewith, means whereby the motor-circuit is opened at said terminals upon the starting of the motor and simultaneously closed independently of the clock mechanism, and means whereby the latter circuit is broken after a predetermined movement of said winding mechanism. 70
6. The combination with clock mechanism of winding mechanism therefor including an electric motor, contact-terminals for closing said motor-circuit at predetermined intervals, one of which terminals is carried by said clock mechanism and yieldingly connected therewith and the other carried by said winding mechanism, means whereby the motor-circuit is opened at said terminals upon the starting of the motor and simultaneously closed independently of the clock mechanism, and means whereby the latter circuit is broken after a predetermined movement of said winding mechanism. 80
7. The combination with clock mechanism, of winding mechanism therefor including an electric motor, contact-terminals for closing said motor-circuit at predetermined intervals, a yielding driving connection between said clock mechanism and one of said terminals, means for locking said terminals in contact during the operation of said clock mechanism, and means controlled by said winding mechanism for releasing said terminals. 90
8. The combination with clock mechanism, of winding mechanism therefor including an electric motor, contact-terminals for closing said motor-circuit at predetermined intervals, a yielding driving connection between said clock mechanism and one of said terminals, means for locking said terminals in contact during the operation of said clock mechanism, means controlled by said winding mechanism for releasing said terminals, and means for latching said yielding terminal after it is released from said other terminal. 100
9. The combination with clock mechanism, of winding mechanism therefor including an electric motor, contact-terminals for closing said motor-circuit at predetermined intervals, and a cam-contact carried by said winding mechanism for opening said circuit. 110
10. The combination with clock mechanism, of winding mechanism therefor including an electric motor, contact-terminals for closing said motor-circuit at predetermined intervals, one of which terminals is carried by said clock mechanism, and a cam-contact operated by said winding mechanism for opening said circuit. 120
11. The combination with clock mechanism, of winding mechanism therefor including an electric motor, contact-terminals for closing said motor-circuit at predetermined intervals, one of which is carried by said clock mechanism and yieldingly connected therewith, and a cam-contact operated by said winding mechanism for opening said circuit. 130
12. The combination with clock mechanism, of winding mechanism therefor including an electric motor having branch circuits, contact-terminals for closing said motor-circuit at predetermined intervals one of which terminals is carried by said clock mechanism, and a cam operated by said winding mechanism, said cam having means co-operating therewith for closing a branch circuit while the motor-circuit is closed through said contact-terminals and for subsequently opening 85 said branch circuit. 140
13. The combination with clock mechanism, of means for automatically winding the same comprising an electric motor, means for closing the circuit of said motor to wind said mechanism after a predetermined amount of spring is uncoiled, means whereby said spring further uncoils to drive said clock mechanism upon the failure of said motor to operate, and means whereby the clock mechanism is positively stopped after said further uncoil. 150
14. The combination with clock mechanism, of means for automatically winding the same comprising an electric motor, means for closing the circuit of said motor to wind said mechanism after a predetermined amount of spring is uncoiled, means whereby said spring further uncoils to drive said clock mechanism upon the failure of said motor to operate, means whereby the energy expended by the 160 said further uncoil is immediately restored when the motor operates, and means whereby the clock mechanism is positively stopped after said further uncoil.
15. The combination with clock mechanism, of winding mechanism therefor including an electric motor, contact-terminals for closing said motor-circuit at predetermined intervals, a yielding driving connection between said clock mechanism and one of the 115 said terminals, means for locking said terminals against relative lateral movement until the clock has been wound, driving connections between said other terminal and said winding mechanism whereby said terminals are unlocked and separated laterally, and means for returning said terminals to contacting position after a predetermined movement of said winding mechanism. 120
16. The combination with clock mechanism, of winding mechanism therefor including an electric motor having a main and auxiliary circuit, contact-terminals for closing the main circuit at predetermined intervals, means operated by said winding mechanism 130

for opening the circuit at said terminals, a cam operated by said winding mechanism, and means in connection therewith for simultaneously closing the auxiliary circuit and for opening the auxiliary circuit after a predetermined movement of said winding mechanism.

17. The combination with clock mechanism of means for automatically winding the same comprising an electric motor, means for periodically closing the motor-circuit to wind said mechanism, and means for operating said mechanism with the motor-circuit closed after the expiration of a period upon failure of said winding means to operate.

18. The combination with clock mechanism of means for automatically winding the same comprising an electric motor, means for periodically closing the motor-circuit to wind said mechanism, means for operating said mechanism for a further period upon the failure of current at the end of said first period, and means for fully winding said mechanism at the end of said second period upon the restoration of current.

19. The combination with clock mechanism of means for automatically winding the same comprising an electric motor, means for periodically closing the motor-circuit to wind said mechanism, means for operating said mechanism for a period with the motor-circuit closed upon the failure of said winding mechanism to operate, and means for positively stopping said mechanism at the end of said period.

20. The combination with clock mechanism of means for automatically winding the same comprising an electric motor, means for periodically closing the motor-circuit to wind said mechanism, means for operating said mechanism for a further period with the mo-

tor-circuit closed upon the failure of current at the end of said first period, and means for fully winding said mechanism at the end of said second period upon the restoration of current.

21. The combination with clock mechanism of means for automatically winding the same comprising an electric motor, means for periodically closing the motor-circuit to wind said mechanism, means for operating said mechanism for a further period upon the failure of current at the end of said first period, means for positively stopping said mechanism at the end of said second period, and means for fully winding said mechanism at the end of said second period upon the restoration of current.

22. The combination with clock mechanism of winding mechanism therefor including an electric motor having branch circuits one of which is closed by the clock mechanism and the other by the winding mechanism, and means whereby the motor-circuit is periodically closed through the former branch and opened through the latter.

23. The combination with clock mechanism of winding mechanism therefor including an electric motor having branch circuits one of which is closed by the clock mechanism and the other by the winding mechanism, means for periodically closing the former branch to start the motor, and means for closing the latter branch and opening the former upon the starting of the motor.

In witness whereof I have hereunto set my hand this 12th day of July, 1905.

GEORGE H. RUPLEY.
